UNITED STATES PATENT OFFICE.

CHESTER S. JENNINGS, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

1,032,141.

Specification of Letters Patent.

Patented July 9, 1912.

Application filed November 5, 1906. Serial No. 342,045.

To all whom it may concern:

Be it known that I, CHESTER S. JENNINGS, of Boston, in the county of Suffolk and State of Massachusetts, have invented certain new and useful Improvements in Pneumatic-Despatch-Tube Apparatus, of which the following is a specification.

My invention relates to improvements in pneumatic despatch tube apparatus and has for its object the automatic control of the power whereby the air current may be reversed for the transmission of carriers through a single transit tube in either direction.

Another object is the control of the power whereby carriers upon discharging automatically shut off the power thereby limiting the use of the same to the interval necessary for the proper transmission and delivery of a carrier.

In the accompanying drawings which illustrate a construction embodying my invention, Figure 1 is a diagram of a single tube pneumatic system embodying my invention and showing electric circuits for controlling the power. Fig. 2 is an enlarged elevation partly in section of the lower part of Fig. 1. Fig. 3 is an enlarged detail of the air reversing valve. Fig. 4 is a vertical section of part of Fig. 1. Fig. 5 is a front elevation partly in section of Fig. 4.

Like letters of reference refer to like parts throughout the several views.

A and B represent respectively a sub-station and a central station connected by a single transmission tube C open to the atmosphere at station A and controlled by a lock valve B' at station B.

C' is an air tube communicating with the transit tube C at its lower end at central station B through a casing or elbow B². The lower end of the air tube C' is connected with the pressure and vacuum ports of the blower D by means of the branch tubes D' and D² respectively. The blower D is driven by the motor M through the belt M'. The connection of the branch tubes D' and D² with the air tube C' is controlled by an air-switch preferably in the form of the rotary valve E pivoted at E' and operated through the crank E² and rod E³ (Fig. 3).

An opening D³ located at the junction of the tubes D' and D² and below the air tube C' is adapted to be controlled by the valve E to connect either of the tubes D' or D² with the atmosphere; thus it will be seen that with the blower in operation and the valve E in the full line position as shown in Fig. 3, the vacuum side of the blower will be in communication with the air tube C' through the branch tube D², while the pressure side of the blower will be free to exhaust into the atmosphere through the branch tube D' and opening D³. This position of the valve will cause a current of air to flow in the transit tube C from station A to station B. In the reverse or dotted line position of the valve E as shown in Fig. 3, a current of air will be circulated in the transit tube C from B to A through the branch tube D' from the pressure side of the blower D thence through the air tube C'; in the meantime, air will be supplied to the vacuum side of the blower through the branch tube D² and opening D³. The position of this valve E is controlled by the lock lever B³ which is connected thereto by means of the arm B⁴, the rod E³ and crank E². When a carrier is to be despatched from station A to station B, the lock lever B³ is in the position shown in Fig. 4 and the valve E in the full-line position as shown in Fig. 3, while the valve B' is held closed by the partial vacuum in the transit tube C until the carrier discharges at station B. If a carrier is to be despatched from station B to station A, the valve B' will have to be locked in closed position by means of lock lever B³ on account of the pressure within the transit tube C. This lock lever B³ upon being closed moves the valve E into the dotted line position Fig. 3 and the current of air is circulated through the tube C from station B to station A in a manner heretofore described.

Located at station B in close proximity to the valve B' is a casing F containing the magnets F' which are adapted to operate upon one end of a bell crank lever F² pivoted at F³, the other end of the lever F² carrying a projection or latch F⁴ adapted when the magnets F' are energized to engage with and lock the lever B³ in closed position.

sition. A spring F^5 is adapted to hold the latch F^4 out of engagement with the lever B^3 when the magnets are deenergized.

Located adjacent to stations A and B are casings G containing the contacts G' and circuit breaker G² pivoted at G³ to the casing G. A trip G⁴ projects into the transit tube C and is adapted to operate the circuit breaker G² when the carrier is traveling in one direction only. The trip G⁴ located near the opposite station is adapted to be operated by a carrier in transit in the tube C in the opposite direction.

Mounted in the cabinet H which contains the motor and blower connections (Fig. 2), is a swing switch S adapted to be operated by a magnet J to cut in or out of operation the motor M in a manner to be hereinafter described.

In despatching a carrier from station A to station B, the carrier is inserted into the opening in the transit tube at A and the operator then presses the button X which energizes the magnet J and closes the swing-switch S and through contacts W W' closing the circuit through the motor M and line wires L' and L² thereby starting the motor, and through blower D causing a current of air to be drawn through the transit tube C from station A to station B, and thence through the blower to the atmosphere as heretofore described, causing the carrier to be despatched from station A through the tube C in the direction of station B. The circuit through the magnet J with the button X closed is as follows: from the batteries Z through wire Z', button X, contact X', wire X² and wire X³, through circuit breaker G², wire X⁴, magnet F' and wire X⁵ to magnet J, thence through wire Z² to batteries Z. In the meantime, the operator has released the button X and the motor controlling or swing-switch S is held closed by means of the insulated bridge piece S' engaging contacts S² and S³ and maintaining the circuit through the magnet J. The circuit closed by bridge-piece S' is now as follows: from the batteries Z through wire Z', wire Z³, circuit breaker G², thence through wire Z⁴ to contact S², through bridge-piece S', contacts S³, wire X⁶, contact Y', wire X², wire X³, circuit breaker G², wire X⁴, magnet F', wire X⁵, magnet J, thence to the batteries Z through wire Z². The carrier in transit in the tube C now engages the trip G⁴ (Fig. 4), just previous to delivering through the valve B' causing the circuit breaker G² to be thrown upward and momentarily out of contact with contacts G' breaking the circuit between wires X³ and X⁴, thereby deenergizing the magnet J and releasing the swing-switch S and breaking contact S² and S³, permanently breaking the circuit through the magnet J. In the meantime the switch S has broken the circuit be-

tween contacts W and W' and the motor M has stopped; the carrier has now discharged through the valve B' at station B.

In despatching a carrier from station B to station A, the operator opens the valve B' and inserts the carrier into the transit tube C. The lock lever B³ is then closed, the rubber cup B⁸ thereon engaging with the valve B' holding the same tightly seated on the opening of the transmission tube C. The button Y is now pushed closing the battery circuit, energizing the magnet F', and through bell crank lever F², the latch F⁴ now engages the projection B⁹ on the lock lever B³ locking the same securely closed. The switch magnet J now being energized, closes the motor-controlling or swinging switch S, as heretofore described, throwing the motor into operation. The closing of the lock lever B³ through rod E³ and crank E², has shifted the valve E into the position shown in dotted lines Fig. 3 causing the air current to flow through the transit tube C from station B to station A and the carrier is despatched toward station A; when the button Y is released, the circuit is maintained as heretofore by bridge-piece S' closing contacts S² and S³, the circuits being identical with those heretofore described. The carrier prior to discharging at station A engages a trip G⁴ similar to that shown in Figs. 4 and 5, momentarily breaking the circuit, deenergizing the magnet J and through the swing-switch S stopping the motor M. The battery circuit having been broken, the magnet F' is deenergized and the latch F⁴, by means of the spring F⁵, is thrown back, releasing the lock lever B³ which allows the valve E to be returned to the normal position shown in full lines Fig. 3 by means of a spring B¹⁰. The carrier has discharged at station A and the valve E is now in position to permit a carrier to be despatched from station A to station B.

Having thus described the nature of my invention and set forth a construction embodying the same, what I claim as new and desire to secure by Letters Patent of the United States is:

1. In pneumatic despatch tube apparatus, a single tube for the transmission of carriers in either direction provided with an opening for the discharge and insertion of carriers, a valve controlling said opening, a pump communicating with said tube, a motor for driving said pump, an air-switch in the communication between the pump and tube for changing the direction of the flow of air in the tube, and mechanism connected with said air-switch adapted to be moved into engagement with said valve when the latter is closed and actuated by the opening of said valve to shift the air-switch to reverse the direction of the flow of air in the tube.

2. In pneumatic despatch tube apparatus, a single tube for the transmission of carriers in either direction provided with an opening for the discharge and insertion of carriers, a valve controlling said opening, a pump communicating with said tube, a motor, for driving said pump, an air-switch normally positioned in the communication between the pump and tube to open the communication to the exhaust side of the pump, and mechanism adapted to be moved into engagement with said valve when the latter is closed and actuated by the opening of said valve to shift said air-switch to open to the pressure side of the pump the communication between the pump and tube. 70
- 10 3. In pneumatic despatch tube apparatus, a single tube for the transmission of carriers, stations located at either end of said tube, an air pump connected with the tube at one of said stations and adapted to supply a current of air through said tube in either direction, a valve normally closed and controlling the opening of said tube adjacent the connection of said air-pump therewith, a motor adapted to operate said air pump, means located at both ends of said stations for starting and stopping said motor, valve-locking means located at 25 the station adjacent the air pump for locking said valve closed, and mechanism actuated by said valve-locking means for reversing the direction of the air current in said tube for the transmission of carriers in either 30 direction between said stations.
4. In pneumatic despatch tube apparatus, a single tube for the transmission of carriers, stations located at either end of said tube, an air pump connected with said tube at one of 40 said stations, a motor adapted to operate said air pump, a valve normally closed and controlling the opening of said tube adjacent the connection of said air pump therewith, air controlling means for normally permitting the transmission of a carrier in 45 one direction through said tube, mechanism adapted to lock said valve and to operate said air controlling means to reverse the current of air in said tube for the transmission 50 of carriers in the opposite direction, and means located at both stations for starting and stopping said motor.
5. In pneumatic despatch tube apparatus, a single tube for the transmission of carriers in either direction provided with an opening 55 for the discharge and insertion of carriers, a pump communicating with said tube, a motor for driving said pump, an air-switch normally positioned in the communication 60 between the pump and tube to open the tube to the exhaust side of the pump, a valve controlling said opening in the tube and operating to close the same through outside air-pressure while the tube is in communication 65 with the exhaust side of the pump, and mechanism adapted to be moved into engagement with said valve when the latter is closed and actuated by the opening of said valve to shift said air-switch to open to the pressure side of the pump the communication between the pump and tube. 70
6. In a pneumatic despatch tube apparatus, a single tube for the transmission of carriers, a sub-station located at one end of said tube, a central station located at the other end of said tube, an air pump connected with said tube at said central station and adapted to supply a current of air to said tube, a motor adapted to operate said air pump, means located at said stations for starting and stopping said motor, and mechanism controlling the connection of said air pump with said tube and adapted to reverse the direction of the current of air through 75 said tube for the transmission of carriers 80 therethrough in either direction.
7. In a pneumatic despatch tube apparatus, a single tube for the transmission of carriers, a sub-station located at one end of said tube, a central station located at the other end of said tube, an air pump connected with said tube at said central station and adapted to supply a current of air to said tube, a motor adapted to operate said air pump, means located at said stations for 85 starting and stopping said motor, and mechanism controlling the connection of said air pump with said tube and adapted to be operated at the central station to reverse the direction of the current of air through said 90 tube for the transmission of carriers 95 therethrough in either direction.
8. In pneumatic despatch tube apparatus, a single tube for the transmission of carriers, a central station located at one end of said tube, a sub-station located at the other end of said tube, an air pump connected with said tube at said central station and adapted to supply the current of air to said tube, a motor adapted to operate said air-pump, means at said stations for starting and stopping said motor, a normally closed valve located at said central station normally permitting the transmission of a carrier from said sub-station to said central station, and locking means adapted to be operated at said central station for locking said valve closed and reversing the current of air through said tube permitting the transmission of a carrier from said central station to said sub-station. 100
9. In pneumatic despatch tube apparatus, a single tube for the transmission of carriers, a central station located at one end of said tube, a sub-station located at the other end of said tube, an air pump connected with said tube at said central station and adapted to supply a current of air to said tube, a motor adapted to operate said air pump, means at said stations for starting 105 and stopping said motor, a normally closed valve located at said central station normally permitting the transmission of a carrier from said sub-station to said central station, and locking means adapted to be operated at said central station for locking said valve closed and reversing the current of air through said tube permitting the transmission of a carrier from said central station to said sub-station. 110
- 115
- 120
- 125
- 130

the said motor, a normally closed valve located at said central station normally permitting the transmission of a carrier from said sub-station to said central station, locking means adapted to be operated at said central station for locking said valve closed and reversing the current of air through said tube and permitting the transmission of a carrier from said central station to said 10 sub-station, and means located adjacent either of said stations adapted to be operated by a carrier in transit thereto for automatically stopping said motor.

10. In pneumatic despatch tube apparatus, a single tube for the transmission of carriers in either direction provided with an opening for the discharge and insertion of carriers, a pump communicating with said tube, a motor for driving said pump, an 15 air-switch normally positioned in the communication between the pump and tube to open the tube to the exhaust side of the pump, a valve controlling said opening in the tube and operating to close the same 20 through outside air-pressure while the tube is in communication with the exhaust side of the pump, locking mechanism for securing said valve closed on said opening, and means actuated by the closing movement of 25 said locking mechanism to shift said air-switch to open the communication between the tube and the pressure side of the pump.

11. In pneumatic despatch tube apparatus, a single tube for the transmission of carriers in either direction provided with an opening for the discharge and insertion of carriers, a pump communicating with said tube, a motor for driving said pump, an 30 air-switch normally positioned in the communication between the pump and tube to open the tube to the exhaust side of the pump, a valve controlling said opening in the tube and operating to close the same 35 through outside air-pressure while the tube is in communication with the exhaust side of the pump, locking mechanism for securing said valve closed on said opening, and means actuated by the closing movement 40 of said locking mechanism to shift said air-switch to open the communication between the tube and the pressure side of the pump, 45 and carrier-actuated means in the tube for releasing said locking mechanism and the latter during its opening movement actuating the air-switch shifting means to turn the switch to open the communication between the tube and 50 pump to the exhaust side of the pump.

12. In pneumatic despatch tube apparatus, a single tube for the transmission of carriers in either direction provided at each end with an opening for the discharge and insertion of carriers, a valve controlling the 55 opening at one end of said tube, a pump communicating with said tube at the end 60

provided with the valve-controlled opening, a motor for driving said pump, an air-switch in the communication between the pump and tube for changing the direction of the flow of air in the tube, mechanism 70 connected with said air-switch and actuated by the opening of said valve to shift the air-switch to reverse the direction of the flow of air in the tube, and means located adjacent to the carrier-discharge opening at 75 the other end of the tube operating to control the opening of said valve.

13. In pneumatic despatch tube apparatus, a single tube for the transmission of carriers in either direction provided at each 80 end with an opening for the discharge and insertion of carriers, a valve controlling the opening at one end of said tube, a pump communicating with said tube at the end provided with the valve-controlled opening, 85 a motor for driving said pump, an air-switch in the communication between the pump and tube for changing the direction of the flow of air in the tube, mechanism connected with said air-switch and actuated 90 by the opening of said valve to shift the air-switch to reverse the direction of the flow of air in the tube, and carrier-actuated means in the other end of said tube adjacent to the carrier-discharge opening therein operating to control the opening of said valve. 95

14. In pneumatic despatch tube apparatus, a single tube for the transmission of carriers in either direction provided at each 100 end with an opening for the discharge and insertion of carriers, a valve controlling the opening at one end of said tube, a pump communicating with said tube at the end provided with the valve-controlled opening, 105 a motor for driving said pump, an air-switch normally positioned in the communication between the pump and tube to open the tube to the exhaust side of the pump, locking means for securing said valve closed, means actuated by the closing movement of 110 said locking mechanism to shift said air-switch to open the communication between the tube and the pressure side of the pump, and means located adjacent to the carrier-discharge opening at the other end of the 115 tube operating to control the releasing of said locking mechanism.

15. In pneumatic despatch tube apparatus, a single tube for the transmission of carriers in either direction provided at each 120 end with an opening for the discharge and insertion of carriers, a valve controlling the opening at one end of said tube, a pump communicating with said tube at the end provided with the valve-controlled opening, 125 a motor for driving said pump, an air-switch normally positioned in the communication between the pump and tube to open the tube to the exhaust side of the pump, locking means for securing the valve closed, 130

means actuated by the closing movement of said locking mechanism to shift said air-switch to open the communication between the tube and the pressure side of the pump, and carrier-actuated means in the other end of said tube adjacent to the carrier - discharge opening therein operating to control the releasing of said locking mechanism.

In testimony whereof, I have signed my name to this specification in the presence of two subscribing witnesses, this eighteenth day of October A. D. 1906.

CHESTER S. JENNINGS.
